CLAIM

The ornamental design for a winglet, as shown and described.

DESCRIPTION

FIG. 1 is a perspective view of the winglet showing our new design;

FIG. 2 is a front view of the winglet of FIG. 1;

FIG. 3 is a rear view of the winglet of FIG. 1;

FIG. 4 is a top view of the winglet of FIG. 1;

FIG. 5 is a bottom view of the winglet of FIG. 1;

FIG. 6 is a side view of the winglet of FIG. 1;

FIG. 7 is another side view of the winglet of FIG. 1; and,

FIG. 8 is a perspective view of the winglet of FIG. 1 shown in an environment of use installed on wings of an aircraft. In FIGS. 1-8, the broken lines in the drawings depict portions of the winglet that form no part of the claimed design. The dot-dash broken lines depict the bounds of the claimed design and form no part thereof. The additional broken lines shown in FIG. 8 depict environmental structure only and form no part thereof.
